UNITED STATES PATENT OFFICE.

JOHN P. COWING, OF CHICAGO, ILLINOIS, ASSIGNOR TO FRANCIS O'SHAUGHNESSY,
TRUSTEE.

BUILDING CONSTRUCTION.

Application filed June 18, 1921, Serial No. 478,483. Renewed April 22, 1925.

To all whom it may concern:

Be it known that JOHN P. COWING, a citizen of the United States, and a resident of the city of Chicago, county of Cook, State of Illinois, has invented an Improvement in Building Construction, of which the following is a specification.

This invention relates to building construction, and more particularly to walls comprising structural units of stone, terra cotta or other material susceptible of being damaged by undue compression.

Among other objects, the invention is intended to supply a structural organization having provision for avoiding the effects of excessive compression stresses, such as are frequently manifested in buildings by the cracking or defacing of stone, terra cotta or other building units. For instance, blocks or tiles forming the exterior surfaces of buildings, and often having only moderate crushing strength, are sometimes found to be so stressed by compressive forces that corners of blocks or tiles are spalled off, leaving exposed mutilations, or whole faces of the blocks or tiles are broken away. Such effects as these are intended to be avoided by the use of the present invention.

The character of the invention will be best understood by reference to one illustrative structure containing an embodiment thereof, which is shown in the accompanying drawings.

In the drawings, Fig. 1 is a vertical cross-section of the illustrative structure.

Fig. 2 is a front elevation thereof.

Fig. 3 is an enlarged detail of a portion of the section shown in Fig. 1.

Fig. 4 is a sectional detail of a portion of a compressible filler employed in the illustrative structure, the section being taken on the line 4—4 of Fig. 3.

The illustrative structure comprises a main wall 5 of concrete or other material, and a facing wall 6 made up of structural units, for instance terra cotta tiles. According to a conventional practice, tie-bolts 7, 8 and 9 are shown anchored in the main wall 5 at vertical intervals to tie thereto iron angle-bars 10, 11 and 12, each presenting a horizontal ledge or shelf which is interposed in the facing wall 6 and affords supporting means for a superposed tier of the tiles. Thus in Fig. 1 a tier of tiles 13, 14 and 15

is shown superposed upon the angle bar 10; 55 a tier of tiles 16, 17 and 18 upon the angle bar 11; and the tile 19 represents the first course of a similar tier of tiles superposed upon the angle bar 12.

Mortar 20 may be employed for bonding the elements of the facing wall where desired. The usual practice has been to bond together the several courses of tiles and interposed angle bars by mortar applied between the courses and around the horizontal ledges of the angle bars, thus forming a substantially solid wall with the supporting shelves or ledges embedded therein. The mortar usually sets to a hardness and compression strength approximating or even 70 exceeding the hardness and compression strength of building units such as stone or terra cotta blocks, tiles or the like. Hence a facing wall or analogous structure, as constructed prior to the present invention, was 75 to such an extent rigid in the vertical direction that the occurrence of successive compression stresses, due to load, temperature expansion or otherwise, would be likely to rupture or deface the tiles or other units 80 composing the structure.

For relieving such conditions, the facing wall of the illustrative structure is provided at intervals with so-called "pressure-relieving joints," adapted to be contracted by expansion of or thrust in the wall structure transversely of the joints, so as to permit yielding or relative play between adjacent superposed sections or zones of the wall and thus avoid the transmission of undue compression stresses to the tiles. The wall elements are or may be bonded by mortar in the usual way, except that no non-yielding binder unites the particular elements between which the pressure-relieving joints 95 are provided.

Three such joints 21, 22, and 23 are represented in the drawings, associated with the respective angle bars 10, 11 and 12, serving to divide the whole tier of tiles into zones, i. e., the zone superposed upon the angle bar 11, and that superposed upon the angle bar 12.

Such a pressure-relieving joint may advantageously be provided between the top 105 of a tier of tiles and the bottom of the supporting angle bar for the next superposed zone of the wall. In other words, the facing

wall may be constructed with the supporting angle bar for a zone spaced above the top of the subjacent zone, the intervening space being filled with a compressible medium or 5 filler. Such a construction, providing a pressure relieving joint which need not be load-sustaining and which may be embodied in a wall structure having superposed zones 10 separately supported independently of each other, possesses certain advantages in the work of erecting such walls; and this construction also lends itself readily to repair work on old walls to convert them from the solid or non-jointed type into the pressure-relieving type exemplified in the present 15 case, as the necessary space for the joint may be cut out under wall-supporting shelves in existing walls.

A desirable form of joint is provided by 20 interposing in the wall—in this instance between a supporting angle and subjacent zone—a compressible filler of the character shown in Figs. 3 and 4 of the drawings. Said filler, in the specific construction illustrated, 25 comprises a sheet of metal folded upon itself to form upper and lower layers 24 and 25, and an intervening corrugated or undulating sheet or metal layer 26 serving to space the layers 24 and 25 apart while 30 adapted to yield under a sufficient pressure to permit the outer layers to be pressed toward each other. The opposite edges of the layers 24 and 25 may be bent toward each other as indicated at 27 in Fig. 4, and 35 the edge of one of the outer layers opposite the fold may be flanged as indicated at 28 in Fig. 3, for completely housing the intermediate corrugated layer, preferably the several layers, including the intermediate 40 corrugated sheet 26, are formed of ductile metal, such as lead; thereby providing a filler composed of layers which are in themselves compressible while at the same time the filler as a whole is compressible apart 45 from compressibility of the material itself. However, such a filler will compress by more or less crunching down of the corrugations of the intermediate layer. If desired, 50 graphite 29 or other lubricant material may be placed between the layers to facilitate relative slippage between the respective layers under the action of excessive compression stresses, promoting a spreading or expansive action of the corrugated layer.

55 The described type of compressible filler, which is exceedingly simple and practicable for the purpose of a pressure-relieving joint, may be usefully employed at any appropriate point in the structure and may be readily 60 designed to withstand a desired dead load or a pre-determined pressure less (by a reasonable margin of safety) than a pressure sufficient to cause fracture or crushing of tiles in the zone or portion of the wall to be protected. Should compression stresses

in excess of such pre-determined pressure be transmitted either through the zone of the wall above or below the filler, whether by weight, temperature expansion, contraction of the supporting structure for the wall, or 70 flexing of the wall (as in the case of vibration of a tower), the filler will yield sufficiently to absorb such excessive stresses. Thus the wall will absorb expansion tendencies and thrust before the pressure becomes 75 great enough to injure the tiles, the compressible filler being designed to sustain, without contracting, such load or thrust as it is called upon to bear, but nevertheless to compress under a pre-determined degree of 80 pressure.

Where, as in the illustrative structure, the filler is interposed between the top of a zone of the wall and the supporting means 85 for a superposed zone, the weight of such superposed zone being sustained wholly or partially by said supporting means, the filler is relieved from pressure except from upward thrust of the subjacent zone of the wall or downward thrust of the supporting 90 means for the superposed zone, as for instance in case of contraction of the main structure of the building carrying the wall supporting angle bars or other supporting 95 means.

As herein represented, the compressible filler rests upon a mortar bed on the topmost tiles of a zone of the wall, and the superposed zone is supported upon a mortar bed supported in part by the angle bar and in 100 part on the filler, the width of the wall and filler in this instance being greater than that of the portion of the angle bar interposed in the wall. The illustrated mortar arrangement is non-essential.

105 The compressible fillers employed in the illustrative structure may be of any desired dimensions within the selection of those skilled in the art to suit the problems encountered, and may be inserted between the courses of tile or elements of the wall structure in layers of any desired length. For example in Fig. 2, the fillers are indicated as formed in sections but joined at their 110 ends as indicated at 30. Division of the wall into zones by a plurality of the illustrative pressure-relieving joints at vertical intervals, will cause excessive pressures arising in the structure in directions transverse of the joints to contract one or more of the compressible fillers, for absorbing such stresses to an extent sufficient to reduce the danger of cracking or spalling off the faces 115 of the structural units.

120 It will be understood that the present invention is not limited to the particular details of construction, organization and mode of operation described, since the details must necessarily be varied appropriately to 125 different problems of construction encoun-

tered in actual building operations and to different materials and types of structures to which the subject-matter of the present invention is to be applied.

5 The main wall 5 of the illustrative structure typifies any main supporting structure or frame work of a building to which a wall construction embodying the present invention is to be applied; and the facing wall 10 6 with its supports provided by the angle bars typifies any structure in which the invention may be embodied. A facing wall of terra cotta tiles is referred to, for illustration, because it represents a type of structure 15 in which the use of the present invention is particularly advantageous because the terra cotta tiles, being designed for lightness, present relatively fragile and vulnerable units in the structure, and 20 it is important to protect them against the damaging effects which would be likely to result from compression stresses in the building unless relieved in the manner indicated.

25 Having thus described my invention, I claim:

1. A wall construction comprising a tier of structural units erected in zones; means for supporting the respective zones substantially independently of each other; and pressure-relieving joints between zones.

2. A wall construction comprising a tier of structural units divided into zones; a compressible filler interposed therein between zones; and independent zone-supporting means for relieving such filler of the weight of the portion of the wall superposed thereon.

3. A wall construction comprising a tier 40 of structural units divided into zones; supporting means for a zone; and a pressure-

relieving joint between said supporting means and a subjacent zone.

4. A wall construction comprising a tier of structural units divided into zones; supporting means for a zone; and a compressible filler between such supporting means and the subjacent zone.

5. A wall construction comprising a tier of structural units divided into zones; supporting means for a zone; and a compressible filler between such supporting means and the subjacent zone, said filler adapted to withstand a desired dead weight without substantial compression but to be contracted by excess pressure.

6. A wall construction comprising a tier of structural units having an interposed compressible filler comprising upper and lower metal layers and an intervening undulating or corrugated metal layer presenting a plurality of supporting surfaces in contact with said upper and lower layers and adapted to be compressed by excessive pressure.

7. A compressible filler for use as a pressure-relieving joint in a wall structure, comprising upper and lower metal layers and an intervening undulating or corrugated layer spacing said upper and lower layers, the latter formed to house said intervening layer.

8. A compressible filler for use as a pressure-relieving joint in a wall structure comprising a sheet of metal folded upon itself and an intervening corrugated metal layer contacting with and spacing the outer layers provided by said folded sheet.

In testimony whereof, I have signed my name to this specification.

JOHN P. COWING.
